United States Patent Office

Des. 194,210
Patented Dec. 11, 1962

194,210

TRANSMITTER-RECEIVER CASING OR SIMILAR ARTICLE

Bernard J. Midlock, Norwalk, Conn., assignor to Laboratory for Electronics, Inc., Boston, Mass., a corporation of Delaware

Filed Sept. 29, 1961, Ser. No. 66,914

Term of patent 14 years

(Cl. D26—1)

FIG. 1

FIG. 2

FIG. 3

FIG. 1 is a side elevational view of a transmitter-receiver casing or similar article showing my new design, the opposite side being substantially a mirror image thereof;

FIG. 2 is a front elevational view thereof;

FIG. 3 is a bottom plan view thereof.

The dominant features of my design are shown in solid lines. The dotted lines are shown for illustrative purposes only.

I claim:

The ornamental design for a transmitter-receiver casing or similar article, as shown and described.
